UNITED STATES PATENT OFFICE.

HUGH GRANT ROBINSON, OF OAKLAND, CALIFORNIA.

HEEL-PLATE.

1,124,062.

Specification of Letters Patent.

Patented Jan. 5, 1915.

Application filed August 20, 1914. Serial No. 857,681.

To all whom it may concern:

Be it known that I, HUGH GRANT ROBINSON, a citizen of the United States, and a resident of Oakland, in the county of Alameda and State of California, have invented 5 a new and Improved Heel-Plate, of which the following is a full, clear, and exact description.

The invention relates to wear plates for 10 the heels of boots and shoes, to equalize the wear on the heel by application to the latter at the zone or area of greatest wear.

Objects of the invention are to provide a 15 wear plate that will eliminate the rasping and metallic sounds incident to metallic wear plates; to provide a wear plate having increased wearing qualities; to provide a wear plate of a character to receive securing 20 nails or the like and increase the holding attributes of the latter; to produce a cushioned effect in a wear plate that offers high 25 wear-resisting properties; and to provide a wear plate of the indicated character that may be cut by a knife or other sharp instrument to any desired size and shape to adapt 30 it to be applied at any desired point on the shoe heel, and quickly and easily secured in place and as readily removed when worn, to be replaced by a new one.

35 The invention will be particularly explained in the specific description following.

Reference is to be had to the accompanying 40 drawings forming a part of this specification, in which similar characters of reference indicate corresponding parts in all the 45 views.

Figure 1 is a perspective view showing a 50 wear plate embodying my invention in use at a worn portion of the shoe-heel; Fig. 2 is a perspective view of a wear plate embodying the invention of a slightly different shape from that illustrated in Fig. 1; Fig. 3 is a perspective view of the strip or body, of said wear plate, the insert being omitted; Fig. 4 is a cross section of the 55 complete wear plate illustrated in Fig. 2; Fig. 5 is a perspective view of a slightly different form of a wear plate; and Fig. 6 is a cross section of still another form.

50 My improved wear plate comprises a body or strip 10 of soft rubber; the same may be bodily curved, as in Figs. 1, 2 and 3. The strip is formed with a groove 11 in the face thereof, longitudinally of the strip, the walls 55 of which overhang or are under cut. In the case of the curved strip the groove follows

the curvature of the strip; and the rear wall 12 conforms to the curvature of a heel α of a boot or shoe A, so that the exterior surface 13 may form a continuation of the 60 lateral heel surface.

In connection with the strip 10 an insert 14 is employed, of a cross section, and of a length to conform to and fill the groove 11. As best seen in Fig. 4, the insert 14 has incorporated therein, spaced layers 15, which are of canvas or similar fabric. The edges of the fabric layers 15 terminate at the face of the wear plate, and the said layers adjacent to the face, are disposed at an angle to 70 the said face. The layers of fabric in the insert 14 alternate with layers of rubber, and the character of the combined insert is such as to give the same less resiliency and more stability than the resilient strip 13. 75 With the layers of fabric disposed as described, edges thereof will be presented at the wear surface at all times; the layers thus have the effect of preventing slipping and eliminating jars as well as the rasping noise 80 incident to the use of metallic plates.

Referring particularly to Fig. 4, it will be observed that the outermost layer 15 of the fabric is comparatively close to the rear wall 12 of the strip, thereby bringing the 85 said outer layer of fabric as close as possible to the back surface of the heel, to offer its wear-resisting qualities at the point of greatest wear. In practice, I first form the insert complete, and then mold the soft rubber 90 about the same, the whole being molded to the desired shape and vulcanized; if desired, the finished device can be cut to vary the shape and size.

In the form shown in Fig. 5, the resilient 95 strip 10^a is essentially straight, and the insert 14^a is correspondingly straight. It is to be understood that the body and strip are otherwise formed as described in connection with Figs. 1 to 4.

In the form shown in Fig. 6, the strip 10^b is of the same character as in the forms above described, and the insert 14 is of hard rubber.

In both of the forms shown in Figs. 5 and 105 6 the strip is dovetailed, the walls being straight, while in Figs. 2 to 4, the insert and the walls of the strip are given rounding lines at the overhanging portions instead of the more strictly dovetail form shown in 110 Figs. 5 and 6. The strips formed as described may be produced in any desired size,

and they may be cut in order to fashion them to conform to a particular portion of the heel *a*. In the shape shown in Fig. 1, the wear plate has been fashioned to present an outer or back surface 13^a corresponding with the under surface and a rear surface of a worn portion of a shoe heel.

In applying the wear plate, shoe nails 18 or equivalent fasteners (Fig. 1) may be employed and driven through the insert from the face thereof, and through the bottom resilient wall 16 of the strip. The character of the insert is such as to prevent the nails from working through the insert and therefore the plate will be securely held in position.

Having thus described my invention, I claim as new, and desire to secure by Letters Patent:

- 20 1. A wear plate for boot and shoe heels, comprising a strip of soft rubber formed with a groove therein extending from end to end of the strip, the side walls of the groove overhanging, and an insert less resilient than the strip and conforming to the overhanging walls thereof, the face of the strip and insert being flush, the insert being adapted to receive fasteners, and the outer surface of the strip being adapted to conform to the lateral surface of a heel.
- 25 2. A wear plate comprising a strip of soft rubber curved bodily in the direction of

length of the strip and having a groove following the curvature of the strip, the walls of the groove overhanging and the outer 35 wall presenting a curve corresponding with the curved lateral surface of a shoe or boot heel, and an insert filling the groove and conforming to the overhanging walls thereof, the said strip being vulcanized to the insert, and the bottom portion of the said strip forming a cushion for the insert, the latter being of less resiliency than the strip and having spaced layers of fabric presenting edges at the face of the inset, the layers of 45 fabric adjacent to the said face being disposed at an angle to the face.

3. A wear plate for boot and shoe heels comprising a strip of soft rubber curved bodily in the direction of the strip and 50 formed with a groove therein following the curvature of the strip and extending from end to end thereof, said strip presenting a back surface rounding to conform to the rear surface of the heel, and an insert less resili- 55 ent than the strip and filling said groove.

In testimony whereof I have signed my name to this specification in the presence of two subscribing witnesses.

HUGH GRANT ROBINSON.
